UNITED STATES PATENT OFFICE.

ERVIN E. STRAWN, OF STORM LAKE, IOWA.

PRINTING-MACHINE.

1,076,613.

Specification of Letters Patent. Patented Oct. 21, 1913.

Application filed March 26, 1912. Serial No. 636,262.

To all whom it may concern:

Be it known that I, ERVIN E. STRAWN, a citizen of the United States of America, residing at Storm Lake, in the county of 5 Buena Vista and State of Iowa, have invented new and useful Improvements in Printing-Machines, of which the following is a specification.

This invention relates to improvements 10 in printing machines and has particular application to machines of this type for printing form letters such as are used in large business houses.

In carrying out the present invention, it 15 is my purpose to provide a printing machine by means of which a form letter may be printed, addressed, and a signature applied thereto, the means for addressing the letter being automatically movable so that 20 a new address may be applied to each letter printed.

In some instances, it may be desirable to 25 put an insert into the body of the letter, therefore, it is a further purpose of my invention to construct a machine of this character whereby letters may be printed, addressed, and an insert applied to the body 30 of the letter, the application of such insert being subsequent to the printing of the body of the letter.

Furthermore, I aim to provide a machine 35 for printing form letters whereby the body of the letter may be printed, an address and salutation applied thereto, and a heading applied to the letter, such as the name of 40 the business house or firm transmitting such letter.

It is also my purpose to provide a printing 45 machine of the class above set forth whereby letters may be printed from a continuous roll of paper and the portion of such paper bearing the letter cut off from the remaining portion automatically.

The invention also involves a machine 50 for printing form letters whereby a letter may be printed, addressed and headed, an insert applied to the body of such letter and a signature attached to the letter, all in one operation.

55 With the above and other objects in view, the invention consists in the construction, combination and arrangement of parts here-

inafter set forth in and falling within the scope of the appended claims.

In the accompanying drawings there has 55 been illustrated one preferred and practical embodiment of my invention, and in these drawings; Figure 1 is a view in side elevation of a printing machine constructed in accordance with the present invention. Fig. 60 2 is a view in elevation of the opposite side of the machine. Fig. 3 is a central longitudinal sectional view of the machine shown in Fig. 1. Fig. 4 is a top plan view thereof. Fig. 5 is an end view looking in a direction 65 toward the left of Fig. 1. Fig. 6 is a transverse sectional view on the line 6—6 of Fig. 1, looking in the direction of the arrow. Fig. 7 is a fragmentary sectional view of 70 the main frame of the machine, one of the printing means being shown in elevation. Fig. 8 is a side elevation of a detail of the invention. Figs. 9, 10 and 11 show a side elevation, vertical and transverse sections, respectively, of another detail of the invention. Fig. 12 is a side elevation of the address forms and their drum. Fig. 13 is a 75 collective view of the operating mechanism of the address forms, and Fig. 14 is a view in elevation of such address forms. 80

Similar reference characters designate like parts throughout the several views.

Referring now to the accompanying drawings in detail, the main frame of the machine is designated at A and in the present 85 instance consists of spaced parallel longitudinal bars 1, 1 connected to each other at one end by a cross bar 2 and equipped at their opposite extremities with legs 3, which legs rest upon a base 4 and may be connected 90 thereto in any suitable manner, if desired, a substantially rectangular or box-like receptacle 5 being mounted upon the base 4 between the legs of the main frame to hold the address forms and other appliances of 95 the machine.

I do not confine myself to a type form of any particular character or to any especial means for mounting the form on the bed, but for illustrative purposes I have shown a 100 form 6 made up of suitable type 7 mounted within a holder or chase 8 which chase is supported upon a bed 9 and held thereto in any suitable manner, the bed 9 being sup-

ported by the longitudinal bars 1, 1 of the main frame of the machine and between the same.

Coöperating with the form 6 is a relatively movable platen, which in the present embodiment of my invention is movable over the form to assist the latter in the printing operation and embodies a roller 10 covered with suitable material, such as rubber 10 or the like, and journaled at its opposite ends in the end walls 11, 11 of the carriage 12, such end walls of the carriage being connected to each other by a cross bar 13 carrying a shield or guard 14 above the 15 roller platen and equipped with a handle 15 by means of which the platen may be moved over the type of the form. The end walls 11 of the carriage terminate at their free ends in depending flanges 16 provided with guide 20 rollers 17 disposed within trackways 18 carried by the outer sides of the longitudinal side bars 1 of the main frame adjacent to the upper edges of such bars, such trackways being of sufficient length to accommodate the 25 movement of the carriage over the form and beyond the same in one direction, for a purpose which will presently appear. If desired, the trackways 18 may be formed in the longitudinal side bars of the frame, and 30 although I have shown one particular form of platen and carriage, it is to be understood that I do not confine myself to this especial construction, as the same is merely shown for the purpose of illustration.

35 In carrying out the present invention, the paper upon which the letter is printed is fed over the form 6 between the same and the platen and from a roll 19 rotatably mounted in brackets 20 formed on the legs 40 3 of the main frame, or detachably connected to such legs, as may be found desirable, at the rear of the form with respect to the direction of travel of the paper during the printing operation. The paper from the 45 roll 19 is fed longitudinally of the machine, at certain intervals and is indicated at *a*, and between such paper and the type of the form 6 is an inking ribbon 21 in the form of a roll 22 mounted upon a shaft 23 journaled 50 in the longitudinal bars 1 of the main frame in advance of the form 6 and disposed within a housing 24, and movable from the roll 22 to a roll 25 and over the type of the form in a direction reverse to that of the 55 travel of the paper subsequent to the printing of the body of the letter.

The address forms, in the present instance, are in the form of a chain 26 composed of a plurality of address plates 27, 60 each of which is provided at one side edge with spaced offset lateral lugs 28 adapted to engage in and between pairs of hooks 29 formed on the adjacent edge of the proximate plates. This chain of address forms is

supported upon an operating drum 30 fixed 65 upon a shaft 31 journaled in the longitudinal bars of the main frame forwardly of the form 6, and between the same and the inking ribbon roll 23, and which drum is preferably of triangular shape and has each side 70 of a width equal to that of the plates of the address forms and has its opposite ends cut out at the angles of the sides, as shown at 32 in Fig. 12, to accommodate the connections between the address plates 27, the intermediate portions of such angles projecting through slots between adjacent plates to rigidly hold the same and impart movement 75 to the chain of such plates.

To print the body of the letter, the type 80 is first set up in the chase to produce a fixed form, and subsequent to the application of the form to the bed, the ribbon 21 is carried over the address plate and type from the roll 23 to the roll 25 and rigidly connected 85 to the latter roll so that in the turning of the latter the ribbon may be moved over the type. The parts being thus positioned, the paper *a* from roll 19, is carried forwardly 90 of the main frame and disposed above the inking ribbon 21 so that upon pressure being applied to the paper, the impression from the type may be transmitted through the inking ribbon to such paper. In order to print the body of the letter from the fixed 95 form, the carriage 12 is moved forwardly, the trackways 18 and rollers 17 facilitating such forward movement, whereby the platen 10 will bear upon the paper *a*, thus producing 100 an impression upon such paper from the type of the fixed form to produce the body of the letter. Subsequent to the printing of the body of the letter, the forward movement of the carriage is continued so that an address and salutation may be applied 105 to the letter from one of the address plates 27, the salutation being carried by such plates as well as the name and address, as shown in Fig. 14. Immediately succeeding this forward movement of the carriage to 110 print the body of the letter and address and salutation, the platen 10 is moved away from the paper so that in the rearward movement of the carriage to its initial operating position, the paper may be moved forwardly as 115 will be hereinafter more fully described, without producing a second impression thereon and thereby smearing the body of the letter. To render the platen inactive at this time upon the paper, the shaft of such 120 platen is journaled in eccentric bearings, in the side walls of the carriage, and each bearing at the opposite sides of the carriage is provided with a lever 33 adapted to engage pins 34 carried by the bars 1 of the 125 main frame and arranged at the limit of the forward movement of the carriage so that upon the carriage reaching its forward

limit of movement, the levers 33 may be 5
acted upon by the pins 34 to rock the bearings and thereby elevate the platen owing to the eccentricity of the bearings. In the
movement of the carriage to its initial position after the printing operation, the levers 33 engage stop pins 35 and thereby rock the platen in an opposite direction to render the same operative for printing purposes.
10 One of the levers 33 may also be connected through the medium of a link 36 with the operating lever 37 of a counter, the counter being designed to register the number of letters printed by the machine, as will be
15 readily understood.

In the movement of the carriage to its initial position after the printing of the body of the letter, the ribbon 21 is moved to present a new inking surface to the type, 20 and for this purpose, I have mounted upon one extremity of the shaft of the roll 25, a ratchet 38 which is fixed to the shaft, and a rocking lever 39 loose upon said shaft and carrying a pawl 40 designed to engage 25 the teeth of the ratchet 38, the lever 39 being actuated about the shaft in one direction by an expansion spring 41 secured at one end to a lug 42 upon the main frame and having its opposite end connected to the lever so that in the movement of the carriage 30 in the printing of the body of the letter, the lever 39 may be actuated about the shaft of the roll 25; the pawl idling upon the ratchet teeth in this movement of the lever 35 and engaging a relatively advanced tooth. The free end of the rocking lever 39 terminates in the path of movement of a pin 43 carried by the carriage 12 so that in the rearward movement of such carriage after 40 the printing operation, the lever 39 may be rocked about the shaft of the ribbon roll 25 and a positive movement imparted to such shaft through the pawl 40 and ratchet 38 to advance the ribbon. As the lever 39 is 45 arranged in the path of movement of the pin 43 upon the carriage, and the carriage operated to print the body of each and every letter, it will be seen that the inking ribbon is advanced to present a new inking 50 surface to the type in a step by step manner and after the printing of each and every letter.

In accordance with the present invention, I utilize an independent printing means for 55 heading the letter, applying an insert to the body of the letter and for affixing a signature to such letter. These several inserts, in the present instance, are all mounted upon a single drum which is designed to be actuated from the platen carriage and in the movement of such carriage to its initial position subsequent to the printing of the body of the letter. This independent printing means in this instance, embodies a drum 44

which carries at one point upon its circumference 65 a plate 45 or other suitable type-carrying medium bearing a letter head, and at an appropriate distance from the plate 45 is another plate 46 or other suitable type carrying medium bearing an insert for the 70 body of the letter, while at a suitable point from the plate 46 is a plate or other form of type bearing member 47 carrying a signature for the letter. The plates 45, 46 and 47 are so arranged relative to one another and 75 the drum so timed with respect to the movement of the carriage, that in the rearward movement of the latter after the printing of the body of the letter, the drum will be rotated to apply a head to the letter, an 80 insert to the body of the letter, and affix a signature to the letter while such letter is in transit and at the proper places. The drum 44, is fixed upon a shaft 48 journaled in the longitudinal bars 1 of the main frame 85 and projected outwardly of one of such bars. In order to transmit motion to the shaft 48, so that the drum 44 may be rotated at the proper time and in the rearward movement 90 of the platen carrying carriage, a suitable form of power transmitting mechanism is arranged intermediate the carriage and the shaft 48 and is operable from the carriage in the movement of the latter to its initial position after the printing of the body of the 95 letter, to impart movement to the drum 44 through the medium of the shaft 48, such mechanism in the present instance consisting of a drum 49 loosely encircling the projecting extremity of the shaft 48 and housing 100 a coiled contractile spring 50 one end of which is connected to the interior of the drum 49, while the opposite end is fixed upon the shaft 48. Formed in the periphery of the drum 49 is a groove 51 into which is 105 fixed one extremity of a flexible element 52, such as a chain, cord, cable or the like having its opposite extremity fastened to a pin 53 carried by one of the side walls of the carriage. Pivotaly mounted upon one side 110 of the drum 49, preferably at diametrically opposite points, are a suitable number of pawls or dogs 54 adapted to engage the teeth of a ratchet wheel 55 keyed upon the shaft 48 in any suitable manner and designed to impart movement to such shaft in 115 the operation of the drum 49 under the action of the flexible element 52.

In the forward movement of the carriage, to assist in the printing of the body of the 120 letter, the spring 50, being a contractile spring, acts to take up the slack in the flexible element 52 and wind the same about the drum 49 and within the groove 51, the pawls 54 in this movement of the drum 125 idling upon the teeth of the ratchet wheel 55. Upon the rearward movement of the carriage subsequent to the printing of the

body of the letter, the drum 49 is rotated against the tension of the spring 50 and the pawls 54 carried by such drum engage the teeth of the ratchet wheel 55 and rotate 5 the same thereby imparting rotary movement to the shaft 48 and the printing drum 44 upon such shaft.

In order to impart a positive movement to the paper *a* subsequent to the printing of 10 the body of the letter and in the movement of the printing drum 44 so that the various inserts carried by such printing drum may be applied to the letter, the printing drum 44 in the present instance at its opposite 15 ends is provided with annular rings 56 which rings bear upon the side edges of the under surface of the paper *a* and act in conjunction with a feed roller 57 disposed preferably immediately above the drum 44, to 20 feed the paper longitudinally of the machine. This roller 57, is preferably mounted upon a shaft 58 journaled at its opposite extremities in blocks 59, 59 slidably mounted within brackets 60 carried by the upper 25 edges of the longitudinal bars 1 of the main frame. Tension springs 61 are interposed between the lower surfaces of the blocks and the bottom walls of the guideways of such blocks in the brackets 60 to place proper 30 tension upon the feed roll 57, set screws 62 being arranged within the upper portions of the brackets 60 to move the blocks 59 and adjust the tension of the springs 61. From this, it will be seen that in the movement of 35 the drum 44, as previously described, the rings 56 and the feed roller 57 will coöperate with one another to feed the paper longitudinally of the machine whereby the inserts carried by the drum may be applied 40 to the letter while such letter is in transit or motion and subsequent to the printing of the body of the letter, it of course being understood that a suitable space is left in the body of the letter so that the insert may 45 be applied thereto.

When the signature has been affixed to the letter, the carriage and consequently the platen have reached their initial operating position and a clean portion of the paper 50 from the roll 19 is disposed above the ribbon 21 so that the above operation of printing may be repeated. As each letter has to have a new address, I have provided means operable automatically and from the carriage to 55 bring a new address plate into position and move the previous address plate out of printing position. To this end, I have mounted upon one extremity of the shaft 31 of the address drum, a ratchet wheel 63 located ad- 60 jacent to the inner side of one of the respective longitudinal bars 1 of the main frame and adapted to be engaged by a dog 64 pivotally mounted upon the carriage 12 as at 65 and adapted to idle upon the ratchet

wheel 63 in the forward movement of the 65 carriage and to rotate such wheel in the rearward movement of the carriage to bring a new name plate into printing position beneath the ribbon 21, the ratchet being constructed in such manner as to release the 70 pawl as soon as the name plate has reached its proper position. A spring 66 is fastened to a suitable part of the main frame and is provided with a detent 67 adapted to receive the edges of the triangular-shaped 75 drum of the address forms so as to retain such forms in proper printing position after the release of the ratchet 63 by the dog 64.

In order to shear or cut the printed portions of the paper into letter form, after the 80 completed printing operation, I make use of a knife 68 pivoted as at 69 to the end of the main frame in advance of the different printing mechanisms and coöoperative with the end bar 2 of such frame to produce a 85 shearing action upon the paper, a spring 70 holds the knife 68 in a normally elevated position and serves to return such knife to its normal position subsequent to the shearing action. This knife 68 is also actuated 90 by the carriage through the medium of a lever 71 pivoted to one of the side bars 1 of the main frame and having one extremity in the path of movement of a pin 72 carried by the carriage, such end of the lever being 95 provided with a hinged joint 73 adapted to present a rigid structure in the forward movement of the carriage so that the latter may swing the lever about its pivotal connection with the main frame and designed to 100 break in the rearward movement of the carriage so that in the latter movement the lever may remain inactive, and connected to the opposite extremity of the lever 71 is a 105 flexible connector 74, such as a chain, cord, cable or the like extending forwardly of the main frame of the machine and trained over a guide pulley 75 and connected at its free extremity to the free end of the blade 68 to 110 operate the latter as aforesaid.

In the construction herein shown, I have provided a table 76 between the knife end of the machine and the printing drum 44, and this table is designed to support or hold a printed letter after the completed printing 115 operation, while the previous letter is cut off by the action of the knife 68. The table 76 therefore always holds a complete letter, but it is to be understood that, if desired, the parts may be so arranged and constructed as to enable the removal of the printed portion of the paper immediately succeeding the completed printing operation.

The inking mechanism for the printing drum 44 comprises in this instance two inking reservoirs 77 and 78 containing red and black ink respectively, the red ink being applied to the insert and the black ink to the 125

letter head and signature, each of the inking reservoirs containing suitable ink rollers 79 to facilitate the application of the ink to the type on the printing drum. Each reservoir 77, 78 is held against the printing drum under tension and in this instance is supported upon a rod 79 journaled in the longitudinal bars of the main frame, the rods being disposed at the opposite sides of the printing drum and mounted one above the other and each carrying coiled expansion springs 80 having one limb 81 in engagement with the respective reservoir and the opposite limb fast in a collar 82 rigidly secured to its respective shaft through the medium of set screws or the like, the springs acting to hold the reservoirs and consequently the rollers under tension and the collars 82 permitting such tension to be varied.

As different colored ink is employed, means is utilized to hold the ink reservoirs out of contact with the drum and the plates until the plate or plates supplied with ink from such reservoirs are brought into proximity to the rollers of such reservoirs. This means in the present instance comprises a pair of disks 83, 84 mounted adjacent to each extremity of the shaft 48 and at suitable distances beyond the ends of the drum 44. These disks 83 and 84 are eccentrically mounted upon the shaft and have their eccentric portions disposed in relatively opposite directions and are adapted to act upon rollers 85, 86 respectively carried by the respective ink reservoirs 78, 77 so that the ink roller of the reservoir 78 will contact with its respective printing plates and the ink roller of the reservoir 77 supply ink to its respective plate. For instance, the active surfaces of opposite disks 83 act upon the rollers 85 of the black ink reservoir 78 to hold the same out of engagement with the drum and consequently the printing plates, until the printing plates 45 and 47 are in proximity to such reservoir, at which time the active portions of the disks release the black ink reservoir and permit its spring to actuate the same into engagement with the plates 47 and 45, the active portions of such disks again engaging the rollers of the reservoir upon the completion of the inking of the plate 45. Similarly, the active portions of the disks 84 engage the rollers 86 of the ink reservoir 77 until the insert plate 46 assumes a position in proximity to the inking roller 79 of such reservoir, at which time the active portions of the disks release the reservoir and permit the inking roller thereof to supply the plate 46 with ink, the active portions of the disks again acting upon the reservoir upon the completion of the inking operation.

In the accompanying drawings, I have

shown a hand operated machine. It is conceivable, however, that the same may be operated from a suitable source of power, as the machine is entirely automatic in its operation, and while I have herein shown and described one preferred form of my invention by way of illustration, it is to be understood that I do not limit myself to the exact details of construction and arrangement of the different mechanisms herein described and delineated, as modification and variation may be made without exceeding the scope of the claims or departing from the spirit of my invention.

I claim:

1. In a printing machine, the combination of a fixed form for printing the body of a letter, a reciprocating platen movable over the form in one direction to assist in the printing of the body of the letter, independent printing means, and means connecting said platen to said independent printing means whereby the latter may be operated in the reverse movement of the platen to apply certain inserts to the body of the letter subsequent to the printing of such letter. 90

2. In a printing machine, the combination of a fixed form for printing the body of a letter, a reciprocating platen movable over the form in one direction to assist in the printing of the body of the letter, independent printing means, means connecting said platen to said independent printing means whereby the latter may be operated in the reverse movement of the platen to apply inserts to the body of the letter subsequent to the printing of such body, and means for rendering the last means inactive upon the independent printing means in the first movement of the platen. 100

3. In a printing machine, the combination of a fixed form for printing the body of a letter, a platen movable over the form in one direction to assist in the printing of the body of the letter, means for moving the sheet bearing such body subsequent to the printing thereof, independent printing means acting upon the body of the letter when the same is in motion to apply an insert thereto, means connecting said platen to said independent printing means to operate the latter, and means holding the last-named means inactive upon the independent printing means in the first movement of the platen. 115

4. In a printing machine, the combination of a fixed form for printing the body of a letter, a movable platen cooperative with the form to print the body of the letter, a plurality of address forms, means for moving a new address form into printing position subsequent to the movement of the platen in the printing of the body of the letter, and independent printing means operable from the movement of the platen to head the letter, 125

apply an insert to the body of such letter, and affix a signature to the same.

5. In a printing machine, the combination of a fixed form for printing the body of a letter, a movable platen coöperative with the form to print the body of the letter, a plurality of address forms, means for moving a new address form into printing position subsequent to the movement of the platen in the printing of the body of the letter, and independent printing means operable from the movement of the platen to head the letter, apply an insert to the body of such letter, and affix a signature to the same subsequent to the movement of the platen to print the body of the letter.

6. In a printing machine, the combination of a fixed form for printing the body of a letter on a portion of paper from a continuous roll, a reciprocating platen coöperative with the form and movable thereover in one direction to print the body of the letter, independent printing means for applying an insert to the body of the letter, and means operable from the platen in the reverse movement thereof to cut the printed portion of the paper from the roll subsequent to the printing of the body of the letter.

7. In a printing machine, the combination of a fixed form for printing the body of a letter on a portion of paper from a continuous roll, a reciprocating platen coöperative with the form and movable thereover in one direction to print the body of the letter, independent printing means for applying a head to the letter, an insert to the body of such letter, and affix a signature thereto, and means operable from the platen in the reverse movement thereof to cut the printed portion of the paper from the roll succeeding the operation of said independent printing means.

8. In a printing machine, the combination of a fixed form for printing the body of a letter on a portion of paper from a continuous roll, a reciprocating platen coöperative with the form and movable thereover in one direction to print the body of the letter, independent printing means for applying an insert to the letter, means for cutting the printed portion of the paper from the roll subsequent to the operation of the independent printing means, and means operable in the reverse movement of the platen to operate said independent printing means and said cutting means.

9. In a printing machine, the combination of a fixed form for printing the body of a letter on a portion of paper from a continuous roll, a platen coöperative with the form to print the body of the letter, independent printing means for applying certain matter to the letter, means operable from said independent printing means to move the paper

longitudinally of the machine subsequent to the printing of the body of the letter, and means operable to cut the printed portion of the paper from the roll subsequent to the operation of said independent printing means.

10. In a printing machine, the combination of a fixed form for printing the body of a letter on a portion of paper from a continuous roll, a platen coöperative with the form to print the body of the letter, means for moving the printed portion of the paper longitudinally of the machine subsequent to the printing of the body of the letter, and independent printing means operable to apply certain matter to the letter while the portion of the paper bearing such letter is in motion, and means operable from the platen to cut the printed portion of the paper from the roll subsequent to the printing of the body of the letter.

11. In a printing machine, the combination of a fixed form for printing the body of a letter on a portion of paper from a continuous roll, a platen coöperative with the form to print the body of the letter, means operable from the platen to feed the printed portion of the paper longitudinally of the machine, and independent printing means operable to apply a heading to the letter, an insert to the body of the letter, and affix a signature thereto in the movement of the paper.

12. In a printing machine, means for printing the body of a letter, means for feeding paper to the first means from a continuous roll, means for moving said paper longitudinally of the machine subsequent to the printing of the body of the letter, independent printing means operable from the first means for heading the letter, applying an insert thereto and affixing a signature to the same in the movement of the paper, and means operable to cut the printed portion of the paper from the roll subsequent to the operation of said independent printing means.

13. In a printing machine, the combination of a fixed form for printing the body of a letter, a platen movable over the form in one direction to assist in the printing of the body of the letter, independent printing means acting upon the body of the letter subsequent to the printing thereof to apply certain inserts thereto, means connecting said platen to said independent printing means to operate the latter, and means for holding the last-named means inactive upon the independent printing means in the movement of the platen to print the body of the letter.

14. In a printing machine, the combination of means for printing the body of a letter, independent printing means acting upon the body of the letter subsequent to the printing

thereof to apply certain inserts thereto, flexible means connecting the first means to said independent printing means to operate the latter, and means for taking up said flexible means in the printing operation of the first-named means whereby the independent printing means is relieved of the influence of said flexible means, said flexible means acting to operate said independent printing

means subsequent to the operation of the 10 first printing means.

In testimony whereof I affix my signature in presence of two witnesses.

ERVIN E. STRAWN.
